TYPEWRITING MACHINE

William A. Dobson, Wethersfield, Conn., assignor
to Underwood Elliott Fisher Company, New
York, N. Y., a corporation of Delaware

Application March 4, 1937, Serial No. 128,898,
which is a division of application Serial No.
49,682, November 14, 1935. Divided and this
application March 18, 1938, Serial No. 196,740

4 Claims. (Cl. 197—114)

This invention relates to line-space and carriage-return levers for typewriters and more particularly to levers of this character having a retractile or foldable finger-piece.

5 In the class of typewriters wherein portability and compactness are requisite, the line-space and carriage-return lever is operatively mounted near the top of the machine and has a forwardly extending arm, the free end of which is disposed for 10 convenient access to the operator. The lever-arm is equipped with a normally upright finger-piece mounted in such manner as to be readily swung downwardly to reduce the overall height of the machine to fit into a carrying case of a minimum 15 depth.

In typing, the finger-piece of the lever is of course repeatedly engaged by the fingers of the typist, usually in such hasty and carefree manner that the typist's fingers may engage or rub against 20 any exposed surfaces of the finger-piece or lever, occasionally resulting in injury due to the presence of exposed screws or other irregular surfaced parts usually required to mount the retractile finger-piece on the lever.

25 The present invention has for its general object the association of a retractile finger-piece with its line-space lever, in a manner to present smooth unbroken contours so as to eliminate any hazards that might cause annoyance or injury to the operator, and to provide such a construction as will substantially conceal the means for attachment of the finger-piece and lever, thus enhancing the appearance of the device.

30 Other features and advantages will hereinafter appear.

This is a division of applicant's co-pending application, Serial No. 128,898, filed March 4, 1937. In an earlier and also co-pending application, Serial No. 49,682, filed November 14, 1935, division 40 was required, and the subject matter divided out was incorporated in the application, Serial No. 128,898. Further division having been required, certain of the subject matter divided out is presented in the present application.

45 In the accompanying drawing,

Figure 1 is a perspective view of a typewriter including the improved line-space and carriage-return lever, and

50 Figure 2 is a detailed perspective view showing a portion of the lever, and the finger-piece detached therefrom.

An Underwood typewriting machine of the portable class is illustrated in the drawing and includes the usual platen 4 rotatably mounted for line-spacing on a carriage 5, the latter being

movable laterally of the machine during typing and return. The carriage 5, in typing, is actuated by the usual drive-spring, the letter-space movement of the carriage being controlled by the usual carriage escapement mechanism. After 5 a line of typing has been completed, the return of the carriage is actuated manually, preferably by engaging a line-space and carriage-return lever 6. In normal typing, the platen is rotated in line-spacing, concomitantly with the actuation 10 of the carriage in its return stroke, the lever 6 being operatively associated with the usual platen line-spacing mechanism, not shown.

The operation of the line-space and carriage-return lever 6 to accomplish the dual functions 15 is well known and therefore a brief description will suffice, to set forth the use of the present invention. The lever 6 is pivotally mounted on the carriage at 7 to swing in a horizontal plane, the lever being formed as a bell crank, an arm of 20 which is flexibly connected at 8 to the usual line-spacing mechanism. The latter mechanism limits the arc of travel of the lever 6 during which travel the platen 4 is rotated the desired line-spacing distance, and as the swinging of the lever 6 is 25 stopped, further actuation of same effects the return movement of the carriage.

For convenient engagement by the fingers of the operator, the lever 6 carries at its free end a finger-piece 9, which is normally disposed to 30 project upwardly from the lever as shown in full lines in Figure 1, and is swingably mounted thereon to be moved into a retracted, substantially horizontal position as shown in dotted outline, when the typewriter is enclosed in its carrying case. A portion of the carrying case is shown in phantom at 10 holding the finger-piece retracted. The finger-piece 9 is shaped to afford a comfortable grip by the operator and has its free end directed angularly so that the finger-piece 9 in normal position, is cammed to swing 40 downwardly as the cover of the carrying case 10 is lowered into position over the typewriter.

As shown more clearly in Figure 2, the lever 6 terminates at its free end in a tubular portion 11 45 having an axial bore 12 extending only partially therethrough so that the bore is closed at the bottom. The finger-piece 9 preferably includes a hub 13 of a size and peripheral contour similar to that of the tubular portion 11 so as to present 50 a smooth unbroken contour and simulate a unitary structure. The finger-piece 9 has a stub-shaft 14 projecting from the hub 13 and preferably integral therewith, the shaft 14 being fitted to rotate without looseness in the bore 12. 55

The length or shape of the shaft 14 in relation to the depth of the bore 12, is such as to afford space within the bore and preferably at the bottom thereof for a torsion spring 15. Spring 15 is preferably formed of a coil of wire having its respective free ends 16, 17, directed axially from the body of the spring, or is otherwise formed so as to impart rotation to the shaft 14 in the bore 12, in a direction to urge the finger-piece 9 to normal upright position. The spring-end 17 is engaged in a recess 18 at the bottom of the bore 12 and the other spring-end 16 engages a recess 19 in the shaft 14. Thus, it will be seen that the pre-formed spring may be inserted into the bore 12 during assembly, to be disposed in the bottom thereof with the spring-end 17 engaged in its recess 18, the spring-end 17 being preferably bent into resilient U form so as to frictionally grip the walls of the recess 18 and prevent unintentional dislodgment of the spring. The shaft 14 is then inserted into the bore, the finger-piece 9 being oriented in relation to the lever 6, so as to align the recess 19 with the spring-end 16 to admit same as the shaft 14 is fully inserted into the bore 12, in which position the end of hub 13 adjacent the shaft 14 abuts the free end of the tubular portion 11.

In order to retain the finger-piece-shaft 14 in assembled relation, and provide a stop to define the normal upright position of the finger-piece 9, the tubular portion 11 is slotted as at 20, the slot 20 being spaced from the free end so as to leave an end portion 21 thereon. The shaft 14 carries a stud 22 which projects radially from the shaft for cooperation with the slot 20. For convenience in assembly, the stud 22 may take the form of a screw insertable into a tapped hole in the shaft 14, the head of the screw being fitted to move freely the slot 20 in contact with the 40 slot wall at the portion 21. It is desired that the slot 20 be disposed in the underside of the lever-arm so as to be normally concealed from view. In the assembled article, the spring 15 yieldably maintains the finger piece 9 in its normal upright position at which the stud 22 engages a corresponding end of the slot 20, the spring 15 being preferably slightly tensioned at its initial setting. The length of slot 20 should be ample to permit the desired swing of the finger-piece 50 9, the stud 22 engaging the wall of slot 20 adjacent the portion 21 to hold the finger-piece in assembly on the lever.

It will be seen from the foregoing that there is provided a novel organization of line-space and 55 carriage-return lever, with a normally upright finger-piece swingably mounted thereon so as to be retractable downwardly for nesting within a carrying case, the combined lever and finger-piece simulating a unitary structure, although 60 the finger-piece is readily swingable to retracted position. It will also be seen that the finger-piece is so organized with the lever as to present a smooth unbroken contour over the entire area of juncture as well as any surfaces thereof likely 65 to be manually engaged, to thus obviate any chance of injury or annoyance to the operator.

What is claimed as new is:

1. In a line-space mechanism for typewriters and the like, two members constituting a manually operable actuating lever and comprising an 70 arm of the lever swingable in a horizontal plane

and a finger-piece carried on the arm, said finger-piece member being normally disposed upright for manual actuation of said lever in one direction and swingable in the opposite direction to or below horizontal position, means for swingably 5 mounting said finger-piece member, including a shaft on one of said members, journaled in the other member, the other member having a closed ended bore journaling said shaft, a spring within the bore yieldably urging said finger-piece member to upright position, and a stud-and-slot device securing said members against relative axial movement and detenting said finger-piece at upright position.

2. In a line-space mechanism for typewriters 15 and the like, a manually operable actuating lever including an arm swingable in a horizontal plane, a finger-piece on said lever-arm in normally upright position for manual actuation of said lever in one direction and swingable in the opposite 20 direction to or below horizontal position, said lever-arm including a tubular portion having a bore closed at one end, a shaft on said finger-piece journaled in the bore, a spring within said bore yieldably urging said finger-piece to upright position, and a stud-and-slot device associated with said tubular portion and shaft to prevent axial movement of said shaft in the bore and detent said finger-piece at upright position. 30

3. In a line-space mechanism for typewriters and the like, a manually operable actuating lever including an arm swingable in a horizontal plane, a finger-piece on said lever-arm in normally upright position for manual actuation of said lever 35 in one direction and swingable in the opposite direction to or below horizontal position, said lever-arm including a tubular portion having a bore closed at one end, a shaft on said finger-piece journaled in the bore, a torsion spring 40 operatively interposed between the closed end of the bore and the corresponding end of said shaft to urge said finger-piece to upright position and having a slidably engagement with said shaft to facilitate assembly, said tubular portion having a slot intermediate its ends, and a stud acting in the slot to prevent axial movement of said shaft in the bore and detent said finger-piece at upright position. 45

4. In a line-space mechanism for typewriters 50 and the like, a manually operable actuating lever including an arm swingable in a horizontal plane, a finger-piece on said lever-arm in normally upright position for manual actuation of said lever in one direction and swingable in the opposite 55 direction to or below horizontal position, said lever-arm including a tubular portion having a bore closed at one end, a shaft on said finger-piece journaled in the bore, a torsion spring operatively interposed between the closed end of 60 the bore and the corresponding end of said shaft to urge said finger-piece to upright position, the respective ends of said spring being directed axially, for engaging corresponding recesses in the bore and shaft, said tubular portion having a slot, and a screw removably carried on said shaft, the head of said screw cooperating with the slot to prevent axial movement of said shaft in the bore and detent said finger-piece at upright position. 70
